UNITED STATES PATENT OFFICE

OTTO E. JOHANSEN, OF CHICAGO, ILLINOIS

CASHIER'S PROTECTIVE DEVICE

Application filed September 17, 1932. Serial No. 633,668.

This invention relates to improvements in cashiers' protective devices and, more especially, such a device adapted for use by cashiers, tellers and others having occasion to handle money in places more or less accessible to the public.

Among the features of my invention is the provision of means in combination with a cashier's window to furnish the person behind the window safety from attacks by robbers, bandits, holdup men, and the like.

Another feature of my invention is the provision in connection with a cashier's protective device of safety means to guard against unintentional operation of the apparatus, which safety means can be secretly released by the occupant of the cage when danger threatens.

Another feature of my invention is the provision of a movable gun carriage that can be operated with the foot so that the gun carriage thereby can be trained upon an attacker even with the hands raised above the head.

In my improved device, means are also provided for discharging the gun with the foot, said means being operated electrically so that the gun can be discharged readily and easily with but a slight movement on the part of the operator.

My improved device is simple in construction and operation and effective in use. Its operation can be easily learned, and it should afford anyone handling money in a cage the maximum amount of security and protection.

The apparatus is all arranged below the money shelf and back of the wall under the window so that it is not visible to the public and, consequently, not subject to detection.

Other features and advantages of my invention will appear more fully as I proceed with my specification.

In that form of device embodying the features of my invention shown in the accompanying drawings—

Figure 1 is a view of the device from inside of the cage; Fig. 2 is a view taken as indicated by the line 2 of Fig. 1; Fig. 3 is a wiring diagram; and Fig. 4 is a view in

side elevation of the money box containing the safety release.

Hereafter in the specification and claims, the term "cashier" will be used to include broadly a teller, or anyone else having occasion to handle money.

As shown in the drawings, 10 indicates the usual cashier's window with the bars 11 and counter or shelf 12 which preferably projects a short distance forward of the window, as indicated by 12a. Below the shelf 12 under the window is the usual front wall 13.

Back of the wall 13 are two pairs of spaced uprights extending from the shelf 12 to the floor 14. The forward pair of these uprights is indicated by 15, 15 and the rear pair by 16, 16. Between the uprights 15 near their upper ends is a transverse rail 17 and a similar rail 18 is provided between the uprights 16. 19 indicates a lower transverse rail centrally arranged carried by the diagonal braces 20.

Mounted on the rails 17, 18 and 19 is a transversely movable gun carriage comprising essentially the upright members 21, 21 joined by cross-braces 22 carrying cross pieces 23 at their upper ends provided with rollers 24 operating on the tracks 17 and 18. The lower ends of the bars 21 are provided with rollers 25 operating on the lower surface of the rail 19.

Mounted on the upper surface of the gun carriage is a gun or revolver 26 with its barrel 27 pointed through a transverse horizontal slot 28 near the upper edge of the wall 13 and under the shelf 12. The gun 26 is preferably mounted on a plate 26a slidably mounted on the gun carriage by means of the rod 26b operating through the blocks 26c. Springs 29 permit recoil of the gun after discharge.

The carriage also carries a solenoid 30, the armature 31 of which is connected through the lever 32 pivoted at 33 to a bar 34 having a pin 35 adapted to engage the trigger 36.

37 indicates a foot lever adapted to be pressed down to make contact to discharge the gun. After the foot lever is pressed

down, the foot comes to rest on the steel plate 38 at the lower part of the carriage to hold the carriage and gun in position at the instant of discharge. The carriage is shifted transversely by means of the toe of the foot which is placed between uprights 21. The foot lever 37 has its ends 37 bent downwardly and pivoted on the ends of the rod 19. One end of the foot lever 37 is connected through the link 39 to the lever 40 in the switch box 41 so that when the foot lever is depressed, an electric circuit is completed through the solenoid 30 to draw the armature 31 and discharge the gun. The details of the wiring will be described hereinafter.

42 indicates a cash box shown in section in Fig. 4. In this box there is a hinged plate 43 yieldingly held in position by a spring 44. It is contemplated that some paper money be supported on the plate 43. When this plate is depressed, it presses down the lever 45 to make contact with the member 46 connected to the wire 47. The lever 45 is connected to the wire 48. When the lever 45 contacts with the member 46, a circuit is completed through the wires 47 and 48. When this circuit is open, the device is inoperative. When it is closed, it is rendered operative. It is contemplated that in the event of a holdup, the cashier will be required to hand out the paper money in the box 42. In taking this money from the shelf 43, he can depress the same, causing the lever 45 to contact with the member 46. The member 46 is made of spring or resilient material so that it will yieldingly hold the lever 45 in contact. A release lever 49 is provided to again raise the lever 45 to reset the safety.

In the wiring diagram in Fig. 3, the solenoid 30, armature 31 and lever 32 leading to the trigger of the gun are shown. 50 and 51 indicate a suitable source of electric supply. The cash box 42 is diagrammatically shown with the wires 47 and 48 leading thereto. These wires are in series with the supply so that the entire device is inoperative unless the lever 45 is in contact with the member 46, as explained above. In Fig. 3, the switch box 41 is diagrammatically indicated. Inside of this box are the contacts 52 and 53 adapted to be closed by movement of the link 39 which is activated by the foot lever 37, as above described.

54 indicates a signal light, preferably a small red light, visible only to the cashier which is in series with the switch 45-46. This light burns whenever the switch 45-46 is closed, thus showing the cashier that the protective device is operative.

55 indicates another solenoid in series with the solenoid 30 so that whenever the gun is fired, the solenoid 55 will draw in the armature 56, causing the bar 57 to close the con-

tacts 58, 58^a to activate warning signals, for example, bell 59 and light 60 which may be disposed where desired to give notice to the police or others that a holdup has been attempted.

61 indicates a spring returning the armature 31 of the solenoid 30 to normal position after firing.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as permissible, in view of the prior art.

What I regard as new, and desire to secure by Letters Patent, is:

1. In combination with a cashier's window, a shelf under the window, a wall under the shelf with a horizontal slot near its upper edge, a transversely movable gun carriage back of the wall, a gun mounted on the gun carriage with its muzzle aimed through the slot in the wall, means on the carriage adapted to be engaged by the foot to shift the same transversely, and means adapted to be operated by the foot to discharge the gun, said means being engageable by the foot that shifts the carriage in all positions of the carriage.

2. Apparatus as claimed in claim 1, in which the means for discharging the gun is operated electrically, and in combination with a money box containing a safety switch controlling the gun-discharging circuit.

3. Apparatus as claimed in claim 1, in which the means for discharging the gun is operated electrically, and in combination with a money box containing a safety switch controlling the gun-discharging circuit, said safety switch being operable by pressure on a part in the money box.

4. Apparatus as claimed in claim 1, in which the means for discharging the gun is operated electrically, and in combination with a money box containing a safety switch controlling the gun-discharging circuit, said safety switch being operable by pressure on a money-supporting member in the money box.

5. Apparatus as claimed in claim 1, in which the means for discharging the gun is operated electrically, and in combination with a safety switch controlling the gun-discharging circuit, and a warning signal in series with the circuit controlled by the safety switch.

6. Apparatus as claimed in claim 1, in which the means for discharging the gun is operated electrically, and in combination with a money box containing a safety switch

controlling the gun-discharging circuit, and a warning signal in series with the circuit controlled by the safety switch.

7. Apparatus as claimed in claim 1, in which the means for discharging the gun is operated electrically, and in combination with a money box containing a safety switch controlling the gun-discharging circuit, said safety switch being operable by pressure on 10 a part in the money box, and a warning signal in series with the circuit controlled by the safety switch.

8. Apparatus as claimed in claim 1, in which the means for discharging the gun is 15 operated electrically, and in combination with a money box containing a safety switch controlling the gun-discharging circuit, said safety switch being operable by pressure on a money-supporting member in the money 20 box, and a warning signal in series with the circuit controlled by the safety switch.

9. In combination with a cashier's window, a shelf under the window, a wall under the shelf with a horizontal slot near its upper edge, vertical supports between the shelf and the floor back of the wall, transverse rails carried by said supports, a gun carriage transversely movable on said rails, a part 25 on the gun carriage adapted to be engaged by the foot to shift said carriage transversely, and means operated by the foot for discharging the gun, said means being engageable by the foot that shifts the carriage 30 and in all positions of said carriage.

35 10. Apparatus as claimed in claim 9, in which the means for shifting the carriage includes a pair of spaced members adapted to accommodate the foot therebetween and in which the means for discharging the gun 40 includes a vertically movable horizontal bar adapted to be engaged by the foot that shifts the carriage.

In witness whereof, I have hereunto set my hand, this 13th day of September, 1932.

45 OTTO E. JOHANSEN.
